LOCK SLIDER

Davis Marinsky, Bronx, N. Y., assignor, by mesne assignments, of one-half to said Davis Marinsky and one-half to Louis H. Morin, Bronx, N. Y.

Application April 20, 1940, Serial No. 330,663

4 Claims. (Cl. 24—205.5)

This invention relates to a novel and improved form of lock sliders for separable fasteners and more particularly to automatic locking means for such sliders. The novel features will be best understood from the following description and the annexed drawing, in which I have shown a selected embodiment of the invention and in which:

Fig. 1 is a perspective view of one form of slider made according to my invention;

Fig. 2 is a side and broken sectional view of the device as seen in Fig. 1 illustrating the same arranged upon parts of stringers;

Fig. 3 is a view similar to Fig. 2 showing parts in a different position; and

Fig. 4 is a view similar to Fig. 2 showing another adaptation of the invention.

The invention is used with the type of separable fastener commonly known as a zipper and in which links on two stringers are coupled and uncoupled by movement of a channeled slider lengthwise of the fastener.

In the construction shown in Figs. 1 to 3 inclusive, 10 represents a slider body comprising a top wall 11 and a bottom wall 12. The walls are joined at the wide end of the slider by a connecting web 13 forming part of the usual diverging channels at said wide end of the slider. The top and bottom walls have inturned side flanges 14 to retain the links 15 of two stringers 16, 17, shown in part of Figs. 2 and 3 of the drawing, against displacement and to aid in coupling the links on the stringers in the usual manner. At 18 is shown a finger piece or pull which may be of the usual or any desired form of construction, and shown as having at least one integral lock pin 19 adjacent the pivot 20 thereof. The lock pin 19 is adapted to extend into the channel of the slider through an opening 21 formed in the top wall.

The pull with the lock pin 19 is of the form usually employed in what is known as a "pin lock" construction and normally, according to the prior art, such a pull is pivoted in a fixed bearing on the top wall 11. However, if any force is exerted on the fastener which tends to separate the two stringers from each other, that force may result in damage to the fastener because of the fact that the lock pin may not be forced out of the channel and in fact usually would not be. To avoid such damage, I provide a bearing for the pivot of the pull which will permit bodily movement of the pivot away from the top wall of the slider and thus permit the lock pin to cam out of the opening 21 when ex-

cessive force is applied to the stringers tending to open the fastener.

According to the present invention, I provide a spring arm, here shown as a flat spring 22, having at its free end an arc-shaped bearing 23 which engages the upper surface of the pivot 20 on the pull. At a point spaced from the pivot, and preferably on the top wall of the slider adjacent the wide end thereof, I secure the spring arm to the slider, as by providing it with a hole 24 through which is passed a rivet 25 which may be headed over as at 26. As plainly shown in the drawing, this rivet and opening are preferably elongated or non-circular so as to prevent rotation of the spring arm on the rivet. This means of fastening the parts together is particularly adaptable to a die cast slider, but other means may be used if found preferable.

Preferably, the bearing 23 is wide enough to engage the pivot between the usual side arms 27 of the pull, although here again other arrangements may be used where found suitable.

In Fig. 4, I have shown a different embodiment of the invention, wherein the spring 22a is provided with a loop 23a to substantially completely surround the pivot 20a of the pull 18a and then the spring may be doubled back on itself so that a double thickness thereof may be secured in place by means of the rivet 25a headed over at 26a. In this form, the rivet is presumed to be round and then the spring arm is held against rotation on the rivet as by means of one or more ears 28 keyed to the slider. In the embodiment of Fig. 4 it will also be seen that the pin lock 19a is nearer to the pivot than in the other embodiment and it is also shown as being disposed on the other side arm than in Fig. 1. It will also be understood, of course, that two pin locks may be used if desired, in any embodiment.

In the embodiment shown in Figs. 1, 2, and 3, it will be seen that the spring arm forces the pivot against the top wall of the slider and that if for any reason a force is exerted on the fastener which will tend to separate the stringers 16, 17 thereof, the lock pin may be cammed upwardly to some such position as indicated in Fig. 3, this result being achieved by a bodily upward movement of the pivot 20 and consequently of the pull and lock pin. The spring arm will of course be made with sufficient strength to resist the normal strain on the pull caused by moving the slider by means of the pull. The spring arm, which may be made of spring metal or any other suitable material, thus forms an operating means 55 for the slider and at the same time provides a

safety device which will permit the lock pin or pins to be cammed out of the slider channel or channels to prevent damage to the fastener.

The device shown in Fig. 4 will operate in the same manner as that just described except that the bearing is specifically different and also the spring will be somewhat heavier because of its double thickness and thus may be used with heavier duty fasteners.

In either embodiment of the invention, the resiliency of the arm forms a means for resiliently urging the bearing towards the top wall, and so, when the stringers are pulled apart without the pull being first lifted to release the lock pin, that pin will merely ratchet over the links without causing any damage to the fastener. When the slider is operated as it should be, however, by first lifting the pull to release the lock pin, then the parts function in the normal way.

While I have shown the invention as embodied in certain specific forms, it is to be understood that various changes may be made without departing from the scope of the invention as defined by the appended claims.

For the purposes of description, the pivot end portion of the pull may be said to comprise the pivot part proper and also means limiting the extent of the pivot, which in the construction shown comprises that part of the arms 27 which extends onto the pivot, the mounting comprising the spring, fits snugly between the limiting means of the pivot end of the pull to retain the pull against lateral displacement or movement on the slider.

I claim:

1. A slider for separable fasteners of the class described comprising a top wall having an opening therein communicating with a channel in the slider, a pull having a lock pin adapted to pass through said opening into said channel, said pull having bifurcated portions at one end thereof joined by a pivot, a spring arm fixed to said slider, the free end of said arm having a bearing engaging said pivot and constituting the sole means for mounting the pull on the slider, the width of said spring arm being such that it occupies substantially the entire area on said pivot between said bifurcated portions to retain the pull against lateral movement, said spring urging said pivot and lock pin into yieldingly locking engagement with said fasteners, said lock element having cam portions adapted to ride over said fasteners against the bias of the spring upon the application of upward pressure to said lock element.

2. The combination with a slider for fastener stringers of the class described, of means forming a pivotal mounting for a slider pull, said means comprising a spring member, one end portion of said member being secured to the slider, the other free yieldable end portion of said member forming a pivot bearing, a pull having a pivot end, means at said pivot end limiting the extent of the pivot portion of the pull, said spring member constituting the sole means for mounting the pull on the slider, and the bearing of said spring member engaging the pivot of the pull, retaining the pull against displacement from the slider and also engaging the limiting means of said pivot end to retain the pull against lateral movement on the slider.

3. The combination with a slider for fastener stringers of the class described, of means forming a pivotal mounting for a slider pull, said means comprising a spring member, one end portion of said member being secured to the slider, the other free yieldable end portion of said member forming a pivot bearing, a pull having a pivot end, means at said pivot end limiting the extent of the pivot portion of the pull, said spring member constituting the sole means for mounting the pull on the slider, the bearing of said spring member engaging the pivot of the pull, retaining the pull against displacement from the slider and also engaging the limiting means of said pivot end to retain the pull against lateral movement on the slider, and the pivot bearing of said spring being substantially hook shaped in form.

4. The combination with a slider for fastener stringers of the class described, of means forming a pivotal mounting for a slider pull, said means comprising a spring member, one end portion of said member being secured to the slider, the other free end portion of said member forming a pivot bearing, a pull having a pivot end, means at said pivot end limiting the extent of the pivot portion of the pull, said spring member constituting the sole means for mounting the pull on the slider, the bearing of said spring member engaging the pivot of the pull, retaining the pull against displacement from the slider and also engaging the limiting means of said pivot end to retain the pull against displacement from the slider and also engaging the limiting means of said pivot end to retain the pull against lateral movement on the slider, and the pivot bearing of said spring comprising a closed loop encircling the pivot of the pull.
